UNITED STATES PATENT OFFICE.

JOHN B. WEISMILLER, OF NEW YORK, N. Y., ASSIGNOR OF ONE-THIRD TO CHARLES H. HESSION, OF BROOKLYN, NEW YORK, AND ONE-THIRD TO WILLIAM BODGE, OF NUTLEY, NEW JERSEY.

SCREW-ADJUSTING DEVICE.

1,185,745.

Specification of Letters Patent. Patented June 6, 1916.

Application filed November 18, 1915. Serial No. 62,203.

To all whom it may concern:

Be it known that I, JOHN B. WEISMILLER, citizen of the United States, and resident of New York, in the county of Bronx and State 5 of New York, have invented certain new and useful Improvements in Screw-Adjusting Devices, of which the following is a specification.

The invention relates to improvements in 10 screw-adjusting devices designed particularly for regulating the spaced relation of the working parts of machinery, and holding the same against accidental displacement incident to the vibration of the moving members; and the object of the invention is to 15 provide a simple device that may be adjustably operated to the finest extent and in which the locking tension upon the screw may be readily increased or diminished to 20 conform with the conditions of various situations.

In describing the invention in detail reference is had to the accompanying drawings, forming a part of this specification, and in 25 which:

Figure 1 represents a side view of a common application of the present invention, parts thereof being shown in section; and Fig. 2 shows a modification of one of the 30 members thereof.

As herein shown, numeral 1 designates an ordinary frame, in which is mounted the relatively slidable journal-box 2, carrying an operating roller 3, arranged for adjustment 35 with respect to an opposing roller 4, journaled in a fixed bearing 5. A spring 6 engages one side of the box 2 and normally tends to outwardly urge the same for the separation of the rollers. A set-screw 7 is 40 screw-threaded in the frame 1, with its inner end engaging the adjustable box in opposition to the spring 6. Exterior of the frame the set-screw is arranged in threaded engagement with the thrust-plate 8, and 45 circling the screw is a spring 9, the opposite ends of which bear against the frame and thrust-plate, exerting an opposing thrust therebetween and tending to clamp and hold the screw by friction against accidental 50 turning movement. Loosely extending through the thrust-plate is a stop-screw 10, the inner end of which is detachably connected to the frame by a screw-thread formed thereon.

On the removal of the stop-screw 10, the 55 thrust-plate 8 may be rotated upon the set-screw in opposite directions for the compression or expansion of the spring 9 to change the tension thereof to suit the varying conditions of different locations of use. 60 The stop-screw 10 is then replaced and the set-screw may then be operated without varying the spaced relation between the frame and thrust-plate. By turning the set-screw it will be obvious that an adjustment will be 65 effected between the frame 1 and the box 2, with a corresponding adjustment between the operating rollers 3 and 4.

In the common form of adjusting means consisting of an ordinary set-screw and lock-nut, difficulty is frequently experienced in making fine adjustments by the tendency of the nut, while being locked, to accidentally turn the set-screw and disturb the effected adjustment. Also, when the nut is loosened 75 for making a new adjustment, gaged by an existing position, an accidental turning movement of the set-screw again occurs, tending to make the new adjustment uncertain. The present invention overcomes these 80 objectional features by maintaining a constant spring tension upon the set-screw and allowing it to be forcibly turned in either direction to any extent without loosening the associated parts. 85

While I have shown the adjusting device as applied to the spacing of rollers, it will be evident that the same may likewise be applied to a variety of adjustable mechanical parts wherein the relatively movable members correspond with the frame 1 and box 2. 90

In the modification shown in Fig. 2, the inner end of the set-screw is provided with a groove 11, which engages a socket 12 formed in the box for effecting the relative 95 movement of the latter in opposite directions, obviating the use of the above-mentioned spring 6, shown in Fig. 1.

What I claim as my invention and desire to secure by Letters Patent, is:

1. In an adjusting device, a relatively fixed member, a member supported adjacent thereto for relative movement in opposite directions, a set-screw threaded in one of said members and controlling the movements 105 of said movable member, a thrust-plate in threaded engagement with said set-screw, a spring disposed to exert an opposing thrust

between said thrust-plate and the threaded member, and means for holding said thrust-plate against rotation.

2. In an adjusting device, a relatively fixed member, a member supported adjacent thereto for relative movement in opposite directions, a set-screw threaded in one of said members and controlling the movements of said movable member, a thrust-plate in threaded engagement with said set-screw, a spring disposed to exert an opposing thrust between said thrust-plate and the threaded member, means for adjusting the thrust of said spring, and means for holding said thrust-plate against rotation.

3. In an adjusting device, a relatively fixed member, a member supported adjacent thereto for relative movement in opposite directions, a set-screw threaded in one of said members and controlling the movements of said movable member, a thrust-plate in threaded engagement with said set-screw, a spring encircling said set-screw and exerting an opposing thrust between said

thrust-plate and threaded member, and a stop loosely engaging said thrust-plate and detachably secured to said threaded member.

4. In an adjusting device, a set-screw, a thrust-plate in threaded engagement with said set-screw, means for exerting an adjustable frictional resistance to the movement of said set-screw in said thrust-plate, and means for holding said thrust-plate against rotation.

5. In an adjusting device, a set-screw, a thrust-plate in threaded engagement therewith, a spring encircling said screw and exerting a tension on said thrust-plate for resisting the rotative action of said set-screw, and means for holding said thrust-plate against rotation.

Signed at New York in the county of New York and State of New York this 16th day of November A. D. 1915.

JOHN B. WEISMILLER.
